DESIGN FOR A SKIN TREATING DEVICE

Carmelena De Filippis, New York, N. Y.

Application June 3, 1938, Serial No. 77,546

Term of patent 7 years

To all whom it may concern:

Be it known that I, Carmelena De Filippis, a citizen of the United States and a resident of New York city, county and State of New York, have invented a new, original, and ornamental Design for a Skin Treating Device, of which the following is a specification, reference being had to the accompanying drawing, forming a part thereof and in which

Fig. 1 is a face view of a skin treating device showing my new design;

Fig. 2 is a vertical edge view;

Fig. 3 is a rear view; and

Fig. 4 is an end elevational view thereof.

I claim:

The ornamental design for a skin treating device, as shown.

CARMELENA DE FILIPPIS.
